UNITED STATES PATENT OFFICE.

FREDERICK JOSEPH HERDLE, OF CHICAGO, ILLINOIS.

MUFFLER.

Application filed April 7, 1924. Serial No. 704,882.

To all whom it may concern:

Be it known that I, FREDERICK JOSEPH HERDLE, a citizen of the United States, and a resident of Chicago, in the county of Cook and State of Illinois, have invented a new and useful Improvement in Mufflers, of which the following is a full, clear, and exact description.

My invention relates to improvements in mufflers, and it consists in the combinations, construction and arrangements herein described and claimed.

An object of my invention is to provide a muffler which is adapted to cause a cold stream of air to flow through and around a stream of exhaust gases and which will also break up the gases and mix the gases with air before expelling the gases from the muffler, whereby the gases will be expelled from the muffler in a steady stream so as to quickly cool the gases.

A further object of my invention is to provide a device of the character described which is especially adapted for engines of twin types, such as the twin six, the two exhaust pipes which extend from the engine being led to the muffler in such a manner as to cause the gases, on entering the muffler from the two exhaust pipes, to mix and flow easily into the muffler instead of bucking each other.

A further object of my invention is to provide a device of the character described which has means to take care of the exhaust gases whether the engine is running at low speed or at high speed.

A further object of my invention is to provide a device of the character described which is constructed of stamped out parts whereby the device may be manufactured at slight expense.

Other objects and advantages will appear in the following specification, and the novel features of the invention will be particularly pointed out in the appended claims.

My invention is illustrated in the accompanying drawings forming part of this application, in which

Figure 1 is a vertical section through the device, a portion thereof being shown in elevation.

Figure 2 is a section along the line 2-2 of Figure 1, and

Figure 3 is a section along the line 3-3 of Figure 1.

In carrying out my invention I provide a casing 1 which is closed at one end by means of a cup-shaped member 2 and at the other end by means of a cap 3. The ends 2 and 3 are provided with openings 4 and 5 through which a pipe 6 extends. The pipe 6 has a flared end 7 which bears against the wall of the end 2 and holds the end in adjusted position on the casing 1. The end 2 has a flange 8 which receives the casing 1 and prevents the lateral movement of the end 2 with respect to the casing 1. The pipe 6 has a threaded end 9 upon which the nut 10 is screwed. It will be noted from this construction that the nut 10 when tightened, locks the covers 2 and 3, casing 1 and pipe 6 together. The cover or end 3 has a ring 11 which is riveted thereto and which is spaced from the inner wall of the cover so as to provide a recess 12 that receives one end of the casing 1.

The means for conveying the gases into the casing is shown in the Figures 1 and 3. It will be noted from Figure 3 that the cover or end 3 is provided with two openings 13 and 14 through which the pipes 15 and 16 project. The pipes 15 and 16 are curved around the pipe 6 so as to direct the gases toward the end of the casing 1 that is provided with the cup-shaped end 2. Figure 1 shows an exhaust pipe 17 in dotted lines, this pipe being connected to the pipe 15 by means of a coupling 18. In like manner the pipe 16 may be connected to an exhaust pipe not shown. The open ends of the pipes 15 and 16 are indicated by numbers 19 and 20 and it will be noted that these ends are adapted to direct the gases toward the opposite end of the casing 1. If only one exhaust pipe is used, one of the openings 13 or 14 may be closed.

The means for muffling the gases and to cause them to flow in a steady stream comprises a conical-shaped tube 21 that has its end 22 spaced from the pipe 6 and has its other end 23 abut the pipe 6. The pipe 6 and the tube 21 are provided with ribs 24 and 25 whereby the tube 21 is prevented from longitudinal movement with respect to the pipe 6. The clamp 26 locks the tube 21 to the pipe 6 and further aids in preventing

any movement of the tube with respect to the pipe. The end 22 of the tube is spaced from the pipe 6 by means of small leaf springs 27.

- 5 The gases formed from the pipes 15 and 16 strike the end 2 and then flow into the space between the tube 21 and the pipe 6. It will be noted from Figures 1 and 2 that the pipe 6 is provided with a helical rib 28.
- 10 The rib is V-shaped in cross section, see Figure 1. The side of the rib which faces the end 22 of the tube 21 is provided with a plurality of openings 29, see Figure 2. The openings are shaped so as to receive the gases of combustion and direct them into the interior of the pipe 6. As soon as the tube 21 has its end 23 closed, all of the gases in the casing pass through the openings 29 before they can be expelled from the pipe.
- 15 In case the engine is running slowly, the openings in the first few turns of the rib 28 will be sufficient to receive all of the gases. In case the speed of the engine is increased, more gases will be forced into the muffler and it will require more of the openings 29 to permit these gases to escape into the pipe 6. There are a sufficient number of openings to permit all of the gases to escape into the pipe 6, even though the engine is running at
- 20 high speed. In this way the muffler provides a novel means for automatically permitting the gases to escape through the pipe 6, whether the engine is running at high or low speed.
- 25 From the foregoing description of the various parts of the device, the operation thereof may be readily understood. As heretofore stated the gases of combustion may be led into the muffler by one or both of the pipes 15 or 16. In case both of the pipes are used the gases will mingle together without abutting each other, due to the shape of the pipes 15 and 16. The gases are reversed in their movement when they strike the end 2. They then flow through the tube 21 and through the openings 29 into the interior of the pipe 6. The side wall of the rib 28 that has the openings 29 therein is bent at such an angle with respect to the exterior surface of the pipe 6, that it will cause the gases to pass through the openings 29. The openings 29 are disposed at such an angle that they direct the gases into the pipe 6 at an angle which is approximately 45° with respect to the longitudinal axis of the pipe 6. The gases are therefore mixed with the air that flows through the pipe 6.
- 30 The end 2 is cup-shaped so as to provide a funnel that receives the air and directs it into the pipe. The air flowing on the outside of the casing 1 also aids in cooling the gases within the casing. The device is ex-

tremely simple in construction and manufactured from stamped out pieces, whereby the cost of manufacturing is reduced to a minimum.

I claim:

1. A muffler comprising a casing having exhaust gas inlet openings, a pipe disposed in said casing, a tube inclosing said pipe, said pipe having a helical rib therein, said rib having openings therein to permit the gases to pass from said casing through said openings and into said pipe, said gases being broken up into small streams by said openings whereby the gases are expelled in a constant stream from said pipe.

2. A muffler comprising a casing having a cup-shaped end, exhaust gas inlet pipes disposed in said casing, a pipe extending through the cup-shaped end and through the opposite end of said casing, the cup-shaped end of said casing being shaped so as to cause a large quantity of air to pass through said pipe, said pipe having a rib therein, said rib having openings therein to permit the gases within the casing to pass through the openings and into the pipe, said openings breaking up the exhaust gases into small streams, whereby the gases will be expelled from said pipe in a constant stream.

3. A muffler comprising a casing, said casing having a pair of diametrically opposed inlet pipes adapted to convey gases, a pipe, said inlet pipes being curved around said pipe and having their inner ends disposed diametrically opposite each other and positioned so as to direct the gases parallel to the longitudinal axis of the muffler.

4. A muffler comprising a casing, said casing having a pair of diametrically opposed inlet pipes adapted to convey gases, a pipe, openings in said pipe, a funnel-shaped member mounted upon said pipe, said inlet pipes being curved around said pipe and having their inner ends disposed diametrically opposite each other, whereby the gases will flow in one direction in said casing and be quietly mixed.

5. A muffler comprising a casing, exhaust gas inlet pipes disposed in said casing, a pipe extending through the casing and terminating at the ends of said casing, said last named pipe being adapted to carry a large quantity of air therethrough, said pipe having a rib therein with openings, the openings in said rib being positioned so as to break up the gases of combustion into small streams and to direct these streams of gases into the pathway which the air takes as it flows through said pipe, whereby the gases will be mixed with the air and will be expelled from said pipe in a constant stream.

FREDERICK JOSEPH HERDLE.
